UNITED STATES PATENT OFFICE.

NILS ENGHOLM ANDERSEN, OF MIAMI, FLORIDA.

EXTENSION-BOOM.

1,163,497.

Specification of Letters Patent.

Patented Dec. 7, 1915.

Application filed July 28, 1915. Serial No. 42,241.

To all whom it may concern:

Be it known that I, NILS E. ANDERSEN, a subject of the King of Norway, and a resident of Miami, in the county of Dade and State of Florida, having declared my intention and petitioned to become a citizen of the United States, have invented a new and Improved Extension-Boom, of which the following is a full, clear, and exact description.

My invention, while applicable to booms generally, is more particularly intended for use on derricks of the mast and boom type, and is especially useful in building construction.

With derricks having ordinary booms and employed on the floor of a building, the sweep of the boom covers a comparatively small area, particularly since the derrick is employed to hoist the material from the street and deposit it on the floor to which it has been raised. The limited area of operations of the ordinary derrick requires great expenditure of time and labor in distributing the material after it is hoisted and deposited on the floor, since steel beams are required to be "bulled", as it is termed, by manual labor. Moreover, an auxiliary portable derrick is required to set the steel elements.

The invention has for its object to provide an extension boom which, when applied to a derrick of the character referred to, employed in building operations, will have a materially increased area of operation whereby to avoid the major portion of the manual labor now necessary.

A further object of the invention is to provide an extension boom which will be unfailing in its operation and reliable as to strength and efficiency.

In carrying out my invention, the extension boom is mounted on a main boom which is pivotally mounted on the foot casting of the mast, and an extension fall rigging is provided controlled by an engine drum, together with safety devices in the way of improved guiding means for the extension boom, locking devices to hold the extension boom in the adjusted position, and a support for the extension boom when withdrawn entirely from the extended position.

The invention will be particularly explained in the particular description following.

Reference is had to the accompanying

drawings forming part of this specification, in which similar characters of reference indicate corresponding parts in all the views, and in which:

Figure 1 is a diagrammatic view showing an elevation of a derrick having my improved extension boom; Fig. 2 is a fragmentary longitudinal vertical section of parts of the main and auxiliary boom, together with locking and guiding elements; Fig. 3 is a side elevation showing the main and extension booms folded against the mast; Fig. 4 is a cross-section on the line 4—4 Fig. 3; and Fig. 5 is a cross-section on the line 5—5 Fig. 3.

In carrying out my invention in accordance with the illustrated example, a mast 10 is mounted to turn on a suitable base 11. The foot casting 12 of the mast has pivoted thereto at 13 the foot casting 14 of a main boom 15 whereby the said boom may fold toward or from the mast 10.

A topping lift is provided to control both the booms from a single drum, the rope or cable having such a running connection with the booms as to equalize and properly distribute the strain. The rope 17 of the topping lift extends upwardly from the drum (not shown) over a guide sheave 17^a at the top of the mast 10, and is rove as follows: from sheave 17^a through a block 17^b on the outer end of the main boom 15, thence back through a standing block 17^c at the mast head, thence outward and through a block 18^a on the outer end of the auxiliary boom 16, thence back through a standing block 18^b at the mast head, and then outward again to the block 18 to which the end of the cable is made fast. The block 18^a is connected with the auxiliary boom 16 by a short length of chain 18^c whereby to position the said block 18^a at the proper angle when the auxiliary boom is retracted, and thereby prevent undue rubbing and wear of the cable.

A hoisting fall designated generally by the numeral 19 is employed, the rigging including a fall block 19^a together with a standing block 19^b carried by the outer end of the extension boom.

In order to adjust the position of the extension boom 16, an extension fall designated generally by the numeral 20 is employed and actuated by a suitable drum (not shown). The rigging of the topping lift elements, hoisting fall, and extension fall, involve only an engine with two drums, one

for the topping lift and one for the hoisting fall 19, the "nigger head" of the engine being used for the extension fall 20. The extension and hoisting falls both come through the foot of the mast and its casing 12 to the engine (not shown).

The cable of the extension fall 20 runs from its drum over pulleys 21, 22, on the main boom 15 at an intermediate point on the latter, and over a pulley 23 on the extension mast at the inner end thereof, the end of the rope being made fast as at 20^a to the extension mast. The pulleys 21, 22, are mounted on a fitting 24 secured to the main boom 15, said fitting including a band 24^a which embraces the extension mast 16 to restrain and guide the same. Similarly, a fitting 25 is secured to the main boom 15 at the outer end and includes a band 25^a guidingly embracing the boom 16.

In order to afford wear surfaces on the extension boom 16 in its movements through the elements 24, 25, the extension boom is formed with longitudinally ranging members 26 preferably in the form of half round rods or bars, which serve also to give free movement to the extension boom. The proper movement of the extension boom is further insured by an interlocking sliding engagement between the inner end thereof and the main boom, for which purpose a longitudinal rib or bar 27 is fixedly secured to the main boom 15 along the face thereof adjacent to the path of travel of the extension boom, said head being undercut in the form of a T-head, as clearly shown in Fig. 4. A co-acting guide member 28 is secured or formed upon the cap or ring 29 on the inner end of the extension boom, and presents a longitudinal slot which is undercut to correspond with the T-head 27, slidingly receiving the latter. Near the outer end the extension boom 16 may have a wear band 30.

In order to hold the extension boom in the adjusted position, extended to a greater or less extent, co-acting stop members are provided on the main and extension booms. These comprise a pawl 31 on the main boom and stop shoulders on the extension boom. Said stop shoulders are provided in the present example by a longitudinal rib or bar 32 on the outer end of the extension boom and a stop block 33 near the inner end of the said boom. The pawl 31 is mounted on a rock shaft 34 having bearings in the fitting 24, said shaft having a lateral arm 35 which is connected to a cord or rope 36, which in practice extends to any convenient point adjacent to the drums controlling the derrick. The pawl 31 is under the influence of a compression spring 37 which in the present example is coiled about a pin 38 (Fig. 2) which enters a recess in the main boom 15.

It is to be understood that the minor de-

tails of the elements pertaining to my improved extension boom may be varied within the limits of the appended claims.

With a boom constructed and arranged as shown, the operation is as follows: The 70 topping lift 17 having disposed the main boom at the desired angle to the mast 10, and having carried the extension boom with it, the topping lift 18 is given the necessary slack and the engineer will be signaled to 75 go ahead on the extension fall 20, winding in the same, whereby the extension boom will be forced outwardly. If the extension boom is desired to be only partially extended, it may be held by the pawl 31 engaging 80 the stop 32, or when completely extended it will be held by the pawl engaging the stop 33, so that retrograde movement of the extended boom will be prevented. It is to be understood that these stops may be applied 85 at any desired points along the extension boom. When it is desired to withdraw the extension boom, an outward movement is given to the same sufficient to release the engagement between the pawl 31 and the adjacent stop shoulder, and a pull on the rope or cord 36 will displace the pawl from the path of the shoulder. The extension fall rope 20 is then slackened, permitting the extension beam to slide downwardly until it comes to 90 a rest on the seat 14^a, the topping lift 17 being in the meantime gradually taken up as the extension boom slides inwardly. When the topping lift is manipulated to swing the booms against the mast as indicated in 95 dotted lines in Fig. 1, and in full lines Fig. 3, it will be seen that the weight of the extension mast is taken up by the seat 14^a so that the guide fittings are relieved of strain.

By the described construction also it will 105 be apparent that the extension boom may be made to cover a great area and at the same time it may be collapsed sufficiently to clear guy ropes (not shown) with which the mast 10 is necessarily equipped in practice.

Having thus described my invention, what I claim as new and desire to secure by Letters Patent, is:

1. A boom comprising a main boom, a fitting on the same at the foot having means to pivotally secure the boom to a support, and presenting a seat at a side thereof, an extension boom slidable on the main boom to or from said seat, means to slide said extension boom outwardly a topping lift common 115 to both booms, a fitting on the said boom near its outer end, said fitting embracing the extension boom, a fitting on the main boom inward from the outer end having a band embracing the extension boom, the said 120 extension boom having a series of longitudinal guide members thereon, a longitudinal rib on one of said booms near the inner end presenting an undercut head disposed 125 toward the other of said booms, a fitting on 130

the said other boom presenting an undercut slot receiving the said head, thereby insuring a sliding inter-engagement between the two booms, co-acting stop means on the respective booms to hold the extension boom at different degrees of extension, and to prevent retrograde movement thereof, and means to swing the two booms on the pivotal connection of the foot of the main boom.

10 2. In a derrick, a mast, a main boom, an auxiliary boom slideable on the main boom to an extended or a retracted position, and a topping lift common to both booms and having a connection with each of said booms.

15 3. In a derrick, a mast, a boom, an auxiliary boom slideable on the main boom to an extended or a retracted position, and a topping lift for the booms, including a cable having running engagement with each

20 boom.

25 4. In a derrick, a mast, a main boom, an auxiliary boom slideable on the main boom to an extended or a retracted position, and a topping lift including a cable running from the mast head, a block on the main boom through which the cable is rove, a standing block at the mast head through which the cable is rove from the main boom, a block on the auxiliary boom through

30 which the cable is rove from said standing block, and a second standing block at the mast head through which the cable is rove from the block on the auxiliary boom, the end of the cable being returned and made

35 fast to said block on the auxiliary boom.

5. A boom comprising a main boom, a fitting thereon at the foot having means to pivotally secure the boom to a support, said fitting presenting a lateral seat, and an ex-

40 tension boom slideable on the main boom to and from said seat.

6. A boom comprising a main boom, means to pivotally mount the same, an extension boom slideable on the main boom,

45 and means establishing guided engagement

between the opposed surfaces of the extension boom and the main boom, said means including a longitudinal rib on one boom terminating in an undercut head disposed in the direction of the boom and a corresponding guide member on said other boom embracing the said head and slidably thereon along the said rib.

7. A boom comprising a main boom, means to pivotally mount the same on a support, an extension boom slideable relatively to the main boom, and a fitting on the main boom presenting a member snugly embracing the extension boom, the said extension boom having a series of guide members ranging longitudinally thereof and slidably encircled by said guide member.

8. A boom comprising a main boom, means to pivotally mount said boom on a support, an extension boom slideable on the main boom, actuating means to move said extension boom outwardly, a fitting on the main boom including a member embracing the extension boom and guiding the same, and co-acting stop means to hold the extension boom at different degrees of extension and prevent retrograde movement thereof, said stop means comprising a plurality of members presenting rearwardly facing stop shoulders on the extension boom, a pawl on the main boom normally disposed in the path of movement of said members and receiving the weight of the extension boom, and means to rock said pawl out of the path of said members when relieved of the weight of the extension boom by the said actuating means.

In testimony whereof I have subscribed my name to this specification in the presence of two subscribing witnesses.
